FOOT REST FOR SHOWER STALLS

Kenneth F. Morrison, 9000 Alexander Ave., South Gate, Calif., and Clayton B. Wood, Paramount, Calif. (116 E. 162nd St., Gardena, Calif.)

Filed Nov. 10, 1960, Ser. No. 62,795

Term of patent 14 years

(Cl. D4—4)

FIGURE 1 is a perspective view of a foot rest for shower stalls showing our new design;

FIGURE 2 is an exploded perspective view of the same;

FIGURE 3 is a top plan view thereof;

FIGURE 4 is a front elevational view;

FIGURE 5 is a rear elevational view;

FIGURE 6 is a bottom plan view; and

FIGURE 7 is a side elevational view.

We claim:

The ornamental design for a foot rest for shower stalls, substantially as shown.
